UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-CARS.

SPECIFICATION forming part of Letters Patent No. 789,293, dated May 9, 1905.

Application filed January 19, 1905. Serial No. 241,721.

To all whom it may concern:

Be it known that I, JOHN F. O'CONNOR, a citizen of the United States, residing in Chicago, in the county of Cook and State of Illinois, have invented a new and useful Improvement 5 in Draft-Rigging for Railway-Cars, of which the following is a specification.

My invention relates to improvements in draft-rigging for railway-cars.

My invention consists in providing the draft-rigging side plates or stop-castings, which extend to the front part of the car, with seats or grooves to receive removable and replaceable bearing-pieces in connection with removable and replaceable bearing-pieces fitting in said seats or grooves and supported by the carry-iron, upon which the coupler draw-bar rests, and operating to limit the lateral or swinging movement of the draw-bar, so that the wear and abrasion incident to the draw 20 striking against the same may be taken by these removable and replaceable bearing-pieces. When these bearing-pieces thus become so worn or abraded as to permit too much lateral movement of the draw-bar, they 25 can be readily removed and replaced by similar new bearing-pieces, thus greatly increasing the life and durability of the side plates or stop-castings.

My invention further consists in the novel construction of parts and devices and in the novel combinations of parts and devices herein shown or described.

In the accompanying drawings, forming a part of this specification, Figure 1 is a side elevation, partly in vertical section, of a draft-rigging embodying my invention. Fig. 2 is a top or plan view partly in horizontal section, and Fig. 3 is a detail perspective view 40 of one of the removable or replaceable bearing-pieces.

In the drawings, A A represent the center sills or draft-sills of a car, to which the side plates or stop-castings are secured. A' is the front or cross sill, A² the buffer-block, A³ the buffer-plate, and A⁴ the carry-iron, all of these parts being of any ordinary, suitable, or

desired construction, and B is the coupler having the customary forked draw-head b and pivotal knuckle b'.

B' is the draw-bar, and B² the draw-bar strap or yoke.

The side plates or stop-castings D extend to the front end of the car and are furnished with the customary stops or shoulders d d' 55 d² d³ for the followers C C' C² C³ to abut against.

E e are tandem-arranged springs located between each pair of followers.

Each of the side plates or stop-castings D 60 is provided at its front end with upright grooves or seats d⁴ d⁵ to receive the upright edges f f' of the removable or replaceable bearing-pieces F, which are preferably of substantially the form shown in the drawings— 65 that is to say, of a segmental hollow-square form with rounded corners, so that the same may surround and inclose the inner front corner D' of the stop-casting D, which lies between the upright grooves or seats d⁴ d⁵. The 70 removable bearing-pieces F may be readily removed and replaced by simply removing the carry-iron, which is removably secured in place by bolts a, having threaded nuts a' and keys a². By this means the draft-rigging 75 itself is relieved from the wear and abrasion due to both longitudinal and lateral movement of the draw-bar and its engagement with the guides or bearings which limit its lateral or swinging movement to guide its front end in 80 its longitudinal movement.

I claim—

1. In a draft-rigging, the combination with a draw-bar and side plates or stop-castings provided near the front end thereof with 85 grooves or seats to receive removable bearing-pieces, of removable bearing-pieces fitting in the grooves or seats of said side plates or stop-castings for the front end of the draw-bar to bear against, substantially as specified. 90

2. In a draft-rigging, the combination with a draw-bar and carry-iron, of side plates or stop-castings extending to the front end of the car and provided with upright grooves or

seats, and removable bearing-pieces having upright edges fitting in said grooves or seats, substantially as specified.

3. The combination with side plates or stop-castings having upright grooves or seats therein adjacent to the front inner corners thereof, and removable bent bearing-pieces embracing the inner front corners of the side plates or stop-castings and having edges fitting in said upright grooves or seats, substantially as specified.

4. The combination with side plates or stop-castings having upright grooves or seats there-

in adjacent to the front inner corners thereof, movable bent bearing-pieces embracing the inner front corners of the side plates or stop-castings and having edges fitting in said upright grooves or seats, and a removable carry-iron supporting and holding said removable bearing-pieces in place, substantially as specified.

JOHN F. O'CONNOR.
